CARTON AND METHOD OF MAKING THE
SAME

Edward M. Perkit, Boston, Mass.

Application July 20, 1933, Serial No. 681,279

3 Claims. (Cl. 93—49)

This invention relates to cartons and particularly paper cartons such as are commonly used as egg boxes and bakery boxes.

One object of the invention is the provision of supports for the carton which maintain the bottom of the carton in raised position.

Another object of the invention is the provision of a carton having a reenforced wall construction and a method of making the same.

10 In the practice of the invention a blank of common construction is employed and is of such size and shape as required for the carton to be produced. Such a blank is provided with longitudinal and transverse crease lines which define those 15 portions which are to form the bottom, the walls and the flaps for securing adjacent walls together. U-shaped portions extending toward parallel adjacent crease lines are formed by cuts in that portion which is to form the bottom of the carton. 20 Diagonal crease lines are provided which define with other crease lines and the edges of the blank those portions which cooperate with other portions to secure the adjacent walls of the carton together. Preferably, the outer portions of the 25 blank are folded inwardly along the longitudinal crease lines upon the inner portions of the blank. The blank is then folded along the transverse crease lines. Opening of the folded blank to form the carton causes the blank to become folded 30 along the diagonal crease lines and causes the projections on the walls to project below the bottom and maintain the bottom in raised position.

35 The invention will be more clearly understood from the following description in conjunction with the accompanying drawings; in which

Fig. 1 is a plan view of a blank suitably creased so that it may be folded to form the carton of the invention;

40 Figs. 2, 3 and 4 are plan views of the blank illustrating different steps in the folding of the blank;

Fig. 5 is a perspective view of the carton fully opened;

Fig. 6 is a perspective detail view of a portion of the cover of the carton partly opened;

45 Fig. 7 is a sectional view upon the line 7—7 of Fig. 2;

Figs. 8 and 9 are sectional views taken upon the lines 8—8 and 9—9 of Fig. 3; and

50 Fig. 10 is a sectional view taken upon the line 10—10 of Fig. 4.

Before explaining in detail the present invention it is to be understood that the invention is not limited in its application to the details of construction and arrangement of parts illustrated in the accompanying drawings, since the invention

is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

5 In the form of the invention illustrated the carton is made from a blank B of rectangular shape and is provided with longitudinal crease lines 10 and 11 spaced apart and from longitudinal edges of the blank. The blank is also provided with transverse crease lines 12, 13, 14 and 15. Preferably, the portions of the crease lines 12, 14 and 15 extending from the longitudinal crease lines 10 and 11 to the adjacent longitudinal edges of the blank may be cut as illustrated at a. The crease lines 13 must of necessity be cut from the crease lines 10 and 11 to the adjacent longitudinal edges of the blank as illustrated at b.

20 The longitudinal crease lines 10 and 11 and the transverse crease lines 12, 13, 14 and 15 define certain areas of the blank which are subsequently to form the bottom 20 of the body of the carton, its rear wall 21, front wall 22 and side walls 23 and 24 together with the flaps 25 at opposite ends of the rear wall 21 and the flaps 26 at the opposite ends of the front wall 22 which cooperate with portions of the side walls 23 and 24 to secure the same to the front and rear walls. In the form 30 illustrated, the crease lines also define a top or cover 28 having a front wall 29 and side walls 30 and 31. The flaps 32 at opposite ends of the front wall 29 cooperate with the side walls 30 and 31 to secure the front wall thereto.

35 The blank from which the carton of the invention is produced is also provided with diagonal crease lines 35 and 36 extending from the point of intersection of the crease lines 10 and 11 with the crease line 14 to the outer edges 40 of the blank. Diagonal crease lines 37 and 38 are also provided extending from the intersection of the crease lines 10 and 11 with the crease line 15 to the outer edges of the blank. Diagonal crease lines 39 and 40 are provided extending from the intersection of the lines 10 and 11 with the line 12 to the outer edges of the blank. The portion 20 which is subsequently to form the bottom is provided with a series of spaced U-shaped portions 44 and 45 formed by cuts 42 and 43 extending respectively to the crease lines 14 and 15.

45 The portions of the blank adjacent the longitudinal edges are first folded inwardly along the longitudinal crease lines 10 and 11 upon 55

the inner portions as shown in Fig. 2. Adhesive is applied, as indicated at *t*, to the triangular portions of the blank which are defined by the diagonal crease lines 35, 36, 37, 38, 39 and 40 and the other crease lines and the other edges of the blank which they intersect. The portion 29 of the blank together with the flaps 32 which have been folded thereon is now folded along the crease line 12 to bring the flaps 32 in engagement with the adhesive coated triangular portions *t* of the portions 30 and 31. The portion 22 together with the flaps 26 folded thereon is folded along the crease line 15 to bring the flaps 26 in engagement with the adhesive coated triangular portions *t* adjacent thereto on the portions 23 and 24 as indicated in Fig. 3. The blank is now folded along the crease line 14 to bring the flaps 25 in engagement with the triangular adhesive coated portions *t* of the portions 23 and 24 adjacent thereto, as indicated in Fig. 4.

It will be noted that each operation in folding the blank takes place while the blank is in a flat position. It will be understood, of course, that separate preformed and creased blanks can be fed into a suitable machine and folded as described or a suitable machine may be provided into which strips of carton-forming material, such as cardboard, is fed and is subsequently creased and cut into blanks as it passes through the machine and these blanks are subsequently folded as described.

When the blank folded as described is opened, the triangular adhesive coated portions *t* are folded along the diagonal crease lines 35, 36, 37, 38, 39, 40, as illustrated in Figs. 5 and 6.

It will be understood that cartons may be produced in accordance with the invention in which the cover is merely provided with a front wall. In such cases, the portions 30, 31 and 32 of the blank would be eliminated.

I claim:

1. The method of making a carton in collapsed condition adapted to be set up for use comprising forming a blank having longitudinal and transverse crease lines, said blank being cut along certain of said crease lines from the edge

of the blank to the point of intersection with another crease line, forming diagonal crease lines extending from said points of intersection to the nearest edge of the blank, and folding said blank inward along said longitudinal and transverse crease lines and securing together triangular portions of the outer surface of the blank each of which is bounded by one of said diagonal crease lines whereby the blank is folded along said diagonal crease lines when the carton 10 is set up. 5

2. The method of making a carton in collapsed condition adapted to be set up for use comprising forming a blank providing integral bottom and cover portions, forming longitudinal 15 and transverse crease lines in said bottom portion, cutting the blank along certain of said crease lines from the edge of the blank to the point of intersection with another crease line, forming diagonal crease lines extending from 20 said points of intersection to the nearest edge of the blank, and folding said blank inward along said longitudinal and transverse crease lines and securing together triangular portions 25 of the outer surface of the blank each of which is bounded by one of said diagonal crease lines whereby the blank is folded along said diagonal crease lines when the carton is set up.

3. The method of making a carton in collapsed condition adapted to be set up for use 30 comprising forming a blank providing integral bottom and cover portions, forming longitudinal and transverse crease lines in both of said portions, cutting the blank along certain of said crease lines from the edge of the blank to the 35 point of intersection with another crease line, forming diagonal crease lines extending from said points of intersection to the nearest edge of the blank, and folding said blank inward along said longitudinal and transverse crease lines and 40 securing together triangular portions of the outer surface of the blank each of which is bounded by one of said diagonal crease lines whereby the blank is folded along said diagonal crease lines when the carton is set up. 45

EDWARD M. PERKIT.
